UNITED STATES PATENT OFFICE.

JOSEPH WISSEN, OF DECATUR, ILLINOIS.

SLED-PROPELLER.

SPECIFICATION forming part of Letters Patent No. 314,210, dated March 17, 1885.

Application filed June 24, 1884. (No model.)

To all whom it may concern:

Be it known that I, JOSEPH WISSEN, a resident of the city of Decatur, county of Macon, and State of Illinois, have invented certain new and useful Improvements in Sled-Propellers, of which the following is a specification.

In the drawings accompanying and forming a part of this specification, Figure 1 is a perspective view of a sled with my device attached. Fig. 2 represents the handle, and Fig. 3 shows the propeller in side elevation.

A is the sled, which may be formed in any suitable manner.

a is a lever, provided with bearings a' a" for the handle.

b represents a cogged segment formed of the lower termination of lever a.

c is a smaller cogged segment adapted to gear with b, and provided with lever-termination d.

e is a bar hinged to lever d.

f is a bar hinged to lever e and provided with receptacle g and set-screw k.

h is a pointed bar adapted to be adjusted in receptacle g.

e is an extension on bar e that limits the upward swinging motion of bar f.

m represents the handle, provided with knobs n n and diminished bearings o o.

p shows the bracket by which the propelling device is attached and supported.

q is a pin inserted in the sled-frame for the purpose of limiting the upward motion of lever d.

ll represent securing-bolts for levers a and d.

In Fig. 1 my device is shown ready for a propelling-stroke, and in Fig. 2 the relation of the various parts is shown at the completion of a stroke.

The propelling is effected by oscillating the levers a, and the power is conveyed to the penetrating points through b c d e f in the order named.

A propelling device is attached to each side of the sled by means of brackets p, and a handle, m, connects the levers a and provides a suitable hand-hold for the operator.

To increase the speed of the sled without increasing the motion of the operator, handle

m is placed in holes a" of the levers a, thereby 50 shortening the leverage.

To change the position of the handle with relation to the sled for the purpose of modifying the position of the operator while oscillating the levers, attaching-bolts ll may be 55 drawn and the relative position of the gearing b c be adjusted as desired.

The handle m is provided with diminished bearings o o, that work so loosely in holes a' a" that one lever may be operated without affecting the other.

Lever d and bar e are so hinged that the smallest angle possible for them to form is shown in Fig. 1.

Projection e', as before stated, is relied on 65 to limit the upward swing of bar f, and consequently whenever the device is in the position indicated in Fig. 1 points h are held firmly against the ground or ice.

Points h may be adjusted in head g, and may 70 also be removed for sharpening or other purposes.

The levers are oscillated by the occupant of the sled, and in turning either lever may be operated, to the exclusion of the other.

In sled-propelling devices heretofore produced it has been necessary to keep the mechanism in swift motion in order to attain to any considerable degree of speed, thereby effecting with great labor what should be effected with ease, as it is observable that of all conveyances a sled on snow well beaten or on ice requires the least power to propel.

In my device, owing to the peculiarity of the gearing, a slow steady motion will propel 85 the sled rapidly, and the manner of applying the power, which consists in pulling back with a motion similar to rowing, provides a beneficial exercise for the entire body.

I claim as new and desire to secure by Letters Patent—

1. The combination, in a sled-propelling device, by means of which a slow steady backward motion similar to rowing is used to impart motion to the sled, of levers a, geared 95 segments b and c, levers d, and suitable means for connecting the said levers d with penetrating points h, as and for the purpose set forth.

2. The combination, in a sled-propelling device, of levers *a*, geared segments *b* and *c*, bars *e*, provided with projection *e'*, bars *f*, provided with receptacles *g* and screws *k*, and penetrating points *h*, adapted to be adjusted in receptacles *g*, as and for the purpose set forth.
3. In a sled-propelling device, the combination of levers *a*, provided with holes *a'* *a''*, and handle *m*, provided with diminished extensio

4. The combination, with levers *a*, geared segments *b* *c*, bars *e* *f*, and point *h*, of attaching-brackets *p*, as and for the purpose set forth.

JOSEPH WISSEN.
